(57) **CLAIM**

The ornamental design for a security sensor, as shown and described.

DESCRIPTION

FIG. 1 is a front bottom perspective view of a security sensor showing my new design;

FIG. 2 is a rear top perspective view of the security sensor shown in FIG. 1;

FIG. 3 is a front elevational view of the security sensor shown in FIG. 1;

FIG. 4 is a rear elevational view of the security sensor shown in FIG. 1;

FIG. 5 is a left-side elevational view of the security sensor shown in FIG. 1;

FIG. 6 is a right-side elevational view of the security sensor shown in FIG. 1;

FIG. 7 is a top plan view of the security sensor shown in FIG. 1; and,

FIG. 8 is bottom plan view of the security sensor shown in FIG. 1.

The broken lines shown in the drawings represent portions of the security sensor that form no part of the claimed design.

1 Claim, 4 Drawing Sheets
